(57) **CLAIM**

The ornamental design for a display screen or portion thereof with animated graphical user interface, as shown and described.

DESCRIPTION

FIG. 1 is the first image in a sequence for a display screen or portion thereof with animated graphical user interface showing our new design;

FIG. 2 is the second image thereof; and,

FIG. 3 is the third image thereof.

The broken line showing of a display screen and elements of the user interface are included for the purpose of illustrating portions of the article and form no part of the claimed design. The appearance of the image transitions sequentially between the images shown in FIGS. 1-3. The process or period in which one image transitions to another forms no part of the claimed design.
